SEWING THREAD

Application filed August 2, 1929. Serial No. 383,092.

My present invention is primarily concerned with sewing threads or strands, with seams and edgings in which such threads or strands are used, and with fabric articles in which the thread serves as a securing means. From a broader aspect the invention is also concerned with fabrics woven or otherwise made up wholly or in part of a multiplicity of distinct strands or threads, each according to my invention.

An object of the invention is to provide a thread which is not subject to rot or deterioration, yet which is inherently resilient to stretch with a resilient fabric through which it is sewed, or of which it is a component part.

Another object is to provide a thread of this character offering a strong frictional resistance to slippage at the thread holes so that when a plurality of laminations of resilient fabric are sewed together and subjected to common stretching strains, the portions of the thread between the thread holes will stretch but there will be no creeping of the laminations relatively to each other.

Another object is to provide an article of resilient fabric sewed with a thread of a resiliency at least as great as that of the fabric and acting to prevent rupture at the seam or thread-line when stretching strains are imposed on the fabric, the fabric article sewed with the thread being wholly devoid of flapping ends of thread likely to be snagged and being readily washable without injury to the thread.

In accordance with a preferred embodiment of the invention, the thread is formed of a plurality of fibrous strands knitted together to form a fairly compact bundle or bunch of interlocking chains of thread loops containing sufficient slack to render the thread highly resilient, being sufficiently rough surfaced to oppose a strong frictional drag at the thread holes, yet being transversely compressible so that it will yield when stitched and pulled through a relatively small needle-produced opening and will not cut the fabric.

The thread may be used in sewing resilient fabric articles of many varieties and regard-

less of whether the fabric be knitted, netted or woven.

For illustrative purposes, I have shown the thread used in the construction of a necktie of the unlined, multifold type formed of heavy woven fabric, cut on the bias and held in folded position by a single line of my improved thread. The thread being firmly anchored at its ends, will not snag on a shirt button and, due to its high resiliency, will stretch with the tie as the latter is pulled or knotted or slipped through a turn-over collar.

My novel thread or strand may also be used as the warp strand, the weft strand or both warp and weft strands of novel woven fabric devoid of rubber or other inherently resilient element, which fabric is yet resilient longitudinally, transversely or both.

The invention may be more fully understood in connection with the accompanying drawings, wherein

Fig. 1 is a greatly enlarged perspective view of a length of my improved thread or strand.

Fig. 2 is a similar view and showing the thread when distended by a longitudinal pull thereon.

Fig. 3 is a broken plan view of a necktie in which a single line of stitching by my improved thread serves as the sole securing means to retain the tie in its properly folded condition, the tie being shown before the stitching is complete and with the needle hanging on the end of the thread.

Fig. 4 is an enlarged transverse sectional view on the line 4—4 of Fig. 3, and

Fig. 5 is a broken longitudinal sectional view somewhat diagrammatic in form and on a further enlarged scale taken approximately on the line 5—5 of Fig. 3.

In Fig. 1 of the drawings I have shown one embodiment of the knitted inherently resilient thread in its normal unstretched condition, and in Fig. 2 I have shown the condition of the thread when under tension. Both of these views are greatly exaggerated in size. The thread in the illustrated embodiment comprises four strands interlocking with each other to produce what approximates four lines of chain knitting with each

line interlocked with at least two of the other lines and with the strands so knitted together that they form a fairly compact bundle or bunch of interlocking chains of strand loops. This thread, when transversely severed at any point, will show at least eight strands in cross section so that it will be apparent that considerable doubling or looping back of the strands is resorted to in order to provide the excess needed for substantial elasticity. This thread is generally rectangular in cross section, its surface is rendered rough by the multiplicity of loops or reentrant and it is bulky enough compared to its density to be transversely compressed.

Fig. 2 is shown in a slightly exaggerated scale, the manner in which the various strands of the thread and the various loops of the strands position themselves, when a stretching strain occurs on the thread. The illustrated four-strand thread may be stretched to approximately one and a quarter times its normal length without exceeding its elastic limit. A thread with more or with less strands can be made within the scope of my invention, but for most purposes the thread disclosed would be preferred.

While special machinery may be desired for producing this thread, it may be formed as the product of an ordinary knitting machine. In effect it constitutes a knitted fabric of width substantially no greater than its thickness.

In Figs. 3 to 5 inclusive, I have shown the manner in which the thread may be used in sewing a four-in-hand necktie. The tie illustrated is, except for the thread, of entirely conventional construction and is of the unlined multifold type relying for substance and body on the quality of fabric which is employed and the number of times that the fabric is folded upon itself rather than on the use of lining material.

This tie includes the usual narrow neck-encircling portion 15 and the folded over, flaring tying ends 16. Each tying end is formed by folding back the edge portions of the necktie material upon themselves. As best seen in Fig. 4, each of the rearwardly turned flaps at the tie ends are folded upon themselves several times, giving considerable body and substance to the tie and the edges of the flaps are folded over each other through substantially their entire length and secured together by a single line of stitching 17.

The tie body is preferably of bias cut, woven fabric rendering it resilient in a longitudinal direction, so that it is substantially self-sustaining against permanent deformation under endwise pulling strains incidental to knotting the tie or slipping it through a collar. The line of stitching 17, however, when formed by my improved thread is at least as resilient as the tie body itself. The

stitching is preferably hand sewn and the two ends of the thread are firmly and permanently anchored at 18, as by knotting or otherwise at both ends so that there are no free or flapping thread ends. 70

It will be noted from Figs. 1 and 2 that the thread is of somewhat irregular polygonal shape (generally flat rectangular) in cross section opposing some frictional resistance to slippage through the thread holes so that when the tie body is pulled the thread, instead of slipping through the holes, will stretch with the tie body between the holes and strongly resist any relative creeping of the various laminations, which might cause the tie to rumple or bulge. When the tie body is released, the tie and thread spring back to their normal position, the thread serving as a supplemental positive returning force to restore the tie to its normal shape. 80

It will be apparent that many articles of manufacture formed of resilient fabric might be advantageously sewed with the thread. For instance, seams connecting the edges of resilient fabric sections will not rupture under normal strains when sewed with my thread. For ordinary curtain fabrics the hem may advantageously be sewed with this type of thread. The lining of an ordinary necktie may be sewed in place with it, and a large variety of woven, knitted or netted fabric articles may have their durability and resistance to permanent deforming strains materially enhanced by judicious use of the thread. It will be obvious that in practically all of these articles the line of stitching will generally parallel the direction of resiliency of the fabric. In the bias cut, woven fabric of the necktie the thread follows the bias cut, whereas with a uniformly resilient knitted fabric the thread might run in any direction. When the device is used in connection with cut hosiery a line of stitching about the top of the hose may be employed to allow for circumferential expansion of the hose top, assuring a snug fit and preventing either permanent stretching or undue binding at this point, and similar relations apply to hat linings. 100

A plurality of parallel strands of my knitted thread may serve as the warp for a woven fabric, used, for instance, for garment belts, and affording resiliency somewhat analogous to that of rubber or rubberized fabric but far less liable to deterioration under the effect of perspiration and in washing. Such composite woven fabric of knitted strands may also be produced with my threads or strands in both the warp and weft, and with resiliency accordingly in both directions. 115

It will thus be seen that there is herein described an article in which the several features of this invention are embodied, and which article in its action attains the various 120 125 130

objects of the invention and is well suited to meet the requirements of practical use.

As many changes could be made in the above construction, and many apparently 5 widely different embodiments of this invention could be made without departing from the scope thereof, it is intended that all matter contained in the above description or shown in the accompanying drawings shall 10 be interpreted as illustrative and not in a limiting sense.

Having thus described my invention, what I claim as new and desire to secure by Letters Patent is:—

15 1. As a new article of manufacture, a washable knitted fibrous sewing thread comprising several inter-knitted strands, said thread being sufficiently longitudinally resilient to permit stretching thereof to an extent approximating one and one-quarter times its 20 normal length, said thread being transversely compressible and having a rough surface resistant to slippage at the thread holes.

2. A knitted elastic sewing thread capable 25 of being stretched to approximately one and one-quarter times its normal length without exceeding its elastic limit, said thread including a plurality of fibrous strands knitted to each other to provide a plurality of interlocked chains of strand loops, said chains 30 forming a unitary transversely compressible longitudinally resilient compact thread.

Signed at New York in the county of New York and State of New York this 31st day of 35 July, 1929.

ISSAKHAR COHEN.
